D 17043

UNITED STATES PATENT OFFICE.

EDWARD T. SCHOONMAKER, OF NEW YORK, N. Y., ASSIGNOR TO THE
ROGERS & HAMILTON COMPANY, OF WATERBURY, CONN.

DESIGN FOR A FORK OR SPOON HANDLE.

SPECIFICATION forming part of Design No. 17,043, dated December 28, 1886.

Application filed November 26, 1886. Serial No. 220,006. Term of patent 14 years.

To all whom it may concern:

Be it known that I, EDWARD T. SCHOONMAKER, a citizen of the United States, residing at New York, in the county of New York and State of New York, have invented a certain new and original Design for Fork and Spoon Handles, of which the following is a specification.

Reference is to be had to the accompanying drawing, which forms a part of this specification, and which shows a spoon whose handle is ornamented in accordance with my design.

The leading and most prominent features of my design are the central stalk, A, which springs from the base B and extends upward along the handle, and the foliate acanthine figures C, a number of which are shown as diverging from each side of the central stalk. The leaf-shaped figures are smaller and their divergence less toward the shank of the spoon, the shape of the whole figure being governed by the shape of the handle, whose upper face is substantially covered thereby. Above the figure formed by the leaves and stalk is a raised bead pattern, D, the individual members of which diminish in size from the top of the stalk along the shank toward the spoon-bowl.

I claim--

1. The design for a fork and spoon handle, consisting of the representation of a central stalk springing from a base at the extremity of the spoon-handle and the foliate figures in relief diverging therefrom upon either side, said figures diminishing in size and in extent of divergence toward the upper end of the stalk, substantially as shown and described.

2. The design for a fork and spoon handle, which consists in the representation of a single stalk-like figure springing from a base at the extremity of the handle and extending toward the shank, the acanthine foliate figures springing from said stalk upon either side throughout its full length, and the raised beaded pattern extending from the top of the stalk outward along the shank, substantially as set forth and illustrated.

In testimony whereof I affix my signature in presence of two witnesses.

EDWARD T. SCHOONMAKER.

Witnesses:

SAML. G. HAYTER,
A. S. VAN VOTE.
